UNITED STATES PATENT OFFICE.

THOMAS A. KUGHLER, OF NEW YORK, N. Y.

DESIGN FOR A PUZZLE-BOARD.

SPECIFICATION forming part of Design No. 32,049, dated December 26, 1899.

Application filed October 16, 1899. Serial No. 733,836. Term of patent 3½ years.

To all whom it may concern:

Be it known that I, THOMAS A. KUGHLER, a citizen of the United States, residing at New York, in the county of New York and State 5 of New York, have invented and produced a new and original Design for a Puzzle-Board, of which the following is a specification, reference being had to the accompanying drawings, forming part thereof.

10 In the drawings forming part of this specification, Figure 1 is a plan view of a puzzle-board, showing my new design; and Fig. 2 is an end view.

15 As shown in the drawings, the leading or material feature of my design consists of a body or base 1 of rectangular contour, from the top surface of which projects a series of pins 2, which are equidistantly arranged to form a square, the sides and center of which 20 are indicated by the pins. The pins 2 are of

cylindrical contour, as at 3, with convex top ends 4. The surface of the base or body between said pins is of irregular convex contour, as at 5, said convex portions being in squares between the sets of four pins and being marked by lines or indentations, as at 6, radiating from the pins. 25

Having fully described my invention, I claim as new and desire to secure by Letters Patent— 30

The design for a puzzle-board, substantially as herein shown and described.

In testimony that I claim the foregoing as my invention I have signed my name, in presence of the subscribing witnesses, this 12th 35 day of October, 1899.

THOMAS A. KUGHLER.
